UNITED STATES PATENT OFFICE.

HERBERT N. NORTHROP AND GUSTAVUS A. TOWLE, OF SOMERVILLE, MASSACHUSETTS;
SAID NORTHROP ASSIGNOR TO SAID TOWLE.

HAIR-CURLER.

1,081,400.

Specification of Letters Patent. Patented Dec. 16, 1913.

Application filed December 23, 1912. Serial No. 738,143.

To all whom it may concern:

Be it known that we, HERBERT N. NORTHROP and GUSTAVUS A. TOWLE, citizens of the United States, residing at Somerville, in the county of Middlesex and State of Massachusetts, have invented new and useful Improvements in Hair-Curlers, of which the following is a specification.

This invention relates to a device for curling or waving the hair, the object of the invention being to provide a device of the character set forth which is formed entirely from one piece of wire bent into suitable form to readily receive and hold a portion 10 of the hair in such a position as to cause the same to be curled, or, if the same is already curled, as in the case of puffs, to hold said puffs in shape so that they will not uncurl or become displaced, and further the device 15 may be used for waving the hair.

The invention consists in a hair curler formed of a single piece of wire in the manner hereinafter described and particularly as set forth in the claims.

Referring to the drawings: Figure 1 is a 25 perspective view of a hair curler made in accordance with our invention, the arm which clamps the hair to the body portion of the device being shown in full lines in the 30 position which it occupies when the device is being used as a waver and in dotted lines in the position which it occupies when the device is being used for curling the hair. Fig. 2 is a perspective view of a modified 35 form of device showing the arm which locks the hair to the body portion of the device detached at its free end therefrom. Fig. 3 is a front elevation of the device illustrated in Fig. 2 showing the arm in full lines in the 40 position which it occupies when in use and in dotted lines in the position which it occupies when detached at its free end from the body portion of the device.

Like numerals refer to like parts through 45 out the several views of the drawings.

In the drawings, referring to Fig. 1, 5 is a wire bent to form a frame 6 having two end portions 7 and 8 and side portions 9 and 10, each of said side and end portions 50 consisting of a single straight section of said wire and together forming a rectangle, said side and end portions lying in a common plane. One end of the wire 5 is bent to form an eye 11 which encircles the body

portion of the wire adjacent to the corner 55 12 of the frame 6. The eye 11 is fastened to the body portion of the wire adjacent to said corner either by solder or by being forced or clamped tightly thereagainst. The other end of the wire 5 extends beyond 60 the corner 12 to form an arm 13 adapted to swing in a plane substantially parallel to said common plane, the free end of said arm being bent to form a hook 14 adapted to engage the side 10 adjacent to the corner 65 15 of the rectangle 6, as shown in full lines in Fig. 1. Said arm may also be bent further downwardly and the hook 14 caused to engage the side 9 adjacent to the corner 16 of the frame 6. The first position, that is, 70 where the arm is shown in full lines, is used when it is desired to wave the hair and the second position, that is, where the arm is shown in dotted lines, is used where it is desired to curl the hair.

The hair is wound around the sides 9 and 75 10 when the arm 13 is unhooked from the body portion of the device—that is, over the side 10 or over the side 9 as the case may be, and the hook, after the hair has 80 been wound around outside of the sides 9 and 10, is caused to engage the side 10 adjacent to the corner 15 when it is desired to wave the hair, or, if it is desired to use the device for curling the hair, then the hair is 85 wound around the wires 9 and 10 for about one-half their length from the corner 12 toward the corner 15 and the arm 13 is bent to the position shown in dotted lines (Fig. 1) and the hook 14 is then caused to engage 90 the side 9 of the rectangular frame 6 adjacent to the corner 16. It is, of course, desirable that the side 10 of the device should remain in a fixed position relatively to the side 9 and in order to accomplish this result the 95 eye 11, as hereinbefore set forth, is fastened to or gripped upon the end 8 adjacent to the corner 12.

In Figs. 2 and 3 a modified form of our invention is illustrated in which all of the 100 different parts of the device are substantially the same except that the end 8' is bent or offset to form a notch 17 and the eye 11 encircles the offset portion 18. This construction makes it impossible for the side 10 to be displaced or for the eye 11 to be moved longitudinally of the end piece 8'. Thus 105 said arm 10 is locked in position without

the necessity of soldering the eye 11 to the end 8' or for squeezing it thereon to prevent its displacement relatively thereto.

In using the device the hair is wound around the sides 9 and 10 of the device while the arm 13 is unhooked from the side 10 or the side 9, as the case may be. Then if it is desired to use the device as a waver, the arm 13 is hooked to the side 10 and if it is desired to curl the hair the arm 13 is hooked to the side 9, as indicated in dotted lines (Fig. 1).

One particular advantage secured by forming the device hereinbefore described in the shape of a rectangle is that there is no tendency for the hook portion of the arm 13 to slip or become displaced longitudinally of the side 10 or the side 9 with which it is engaged, as would be the case if the wire forming the end 7 were bent in the form of a semi-circle or curve.

Another advantage consists in having the side and end portions of said rectangular frame formed by straight sections of the wire, as such a construction has a better effect in producing the curls and waves desired and also the device is very simple and easy to manufacture automatically by machinery, thus conducing to cheapness in the cost.

Having thus described our invention, what we claim and desire by Letters Patent to secure is:

1. A hair curler formed of a single piece of wire bent to form a frame consisting of two end portions and two side portions, each of said side and end portions consisting of a single straight section of wire and together forming a rectangle, said side and end portions lying in a common plane, one end of said wire bent to form an eye en-

circling and fast to the body portion of said wire adjacent to one corner of said rectangular frame, the other end of said wire extending beyond said corner to form an arm, the free end of said arm being bent to form a hook adapted to engage the body portion of said wire adjacent to a corner of said rectangular frame at the end thereof opposite to that end at which said eye portion is located, said arm adapted to swing in a plane substantially parallel to said common plane.

2. A hair curler formed of a single piece of wire bent to form a frame consisting of two end portions and two side portions, each of said end and side portions consisting of a single straight section of said wire and together forming a rectangle, said side and end portions lying in a common plane, one end of said wire being bent to form an eye encircling the body portion of said wire adjacent to one corner of said rectangular frame, the portion of said wire encircled by said eye being offset to form a notch therein, the other end of said wire extending beyond said corner to form an arm, the free end of said arm being bent to form a hook adapted to engage the body portion of said wire adjacent to a corner of said rectangular frame at the end thereof opposite to that end at which said eye portion is located, said arm adapted to swing in a plane substantially parallel to said common plane.

In testimony whereof we have hereunto set our hands in presence of two subscribing witnesses.

HERBERT N. NORTHROP.
GUSTAVUS A. TOWLE.
